LAUNDRY MACHINE MECHANISM

Walter A. Frantz, Cleveland Heights, and John J. McCabe, Cleveland, Ohio, assignors to The Apex Electrical Manufacturing Company, Cleveland, Ohio, a corporation of Ohio

Original applications May 27, 1932, Serial Nos. 614,000 and 614,001. Divided and this application December 12, 1933, Serial No. 702,020. In Canada January 9, 1933

20 Claims. (Cl. 74—81)

This invention relates to washing machines and in particular to the operating mechanisms thereof and it constitutes a division of our copending applications Serial No. 614,000 and Serial No. 614-001, both filed on May 27, 1932.

One of the objects of this invention is to provide a washing machine operating mechanism of unitary construction, in which the motor and other operating elements of the mechanism can be assembled and tested as a unit separate from the machine.

Another object of this invention is to provide in a machine of the type disclosed, a simple and compact washer drive mechanism, in which the majority of the operating elements are grouped for movement about a common axis.

Another object of this invention is to provide in a machine of the type disclosed, an improved means for starting and stopping the operation of the dasher or agitator.

A further object of this invention is to provide in a machine of the type disclosed, a generally improved and simplified mechanism embodying a minimum number of parts, which are designed and assembled so as to permit the manufacture of such a machine by modern high speed factory production methods.

With these and other objects in view, the invention consists in the novel construction, arrangement and combination of parts, hereinafter described and illustrated in some of its embodiments in the accompanying drawings, and particularly pointed out in the appended claims.

In the drawings:

Figure 1 is a plan view, partly in section, of our improved washer or agitator driving mechanism with the parts shown in agitator driving position.

Figure 2 is a fragmentary view corresponding to Figure 1, showing the agitator driving gears in their disengaged position.

Figure 3 is a plan view of a modified form of certain gearing details which can be substituted for some of the elements of the gearing shown in Figures 1 and 2.

Figure 4 is a sectional view taken on line 4—4, Figure 1.

Figure 5 is an enlarged sectional view taken on line 5—5, Figure 3.

Figure 6 is a sectional view taken on line 6—6, Figure 1.

Figure 7 is a plan view corresponding to Figure 3 showing the agitator driving gears in disengaged position; and

Figure 8 is a plan view of reduced size showing the gears of the gear shifting control device.

Referring to the arrangement illustrated in Figure 1 the numeral 1 indicates a washer tub which is provided for the purpose of effecting therein the washing of clothes and other articles. The tub is preferably formed from a steel stamping to which a coating of vitreous enamel has been applied. A suitable base 2 is provided for supporting the tub and in order to prevent chipping of the enamel of the tub it is preferred to interpose a number of rubber supporting pads 9 between the tub 1 and its supporting base 2.

The washing operation is effected by means of an oscillatable dasher or agitator 3 which extends upwardly from the bottom of the washer tub 1 and it is mounted to turn about a vertical axis. The agitator 3 is driven by a motor 4 which is supported beneath the washing compartment 1 and connected in driving relation to the agitator 3 through suitable gearing which will be described in detail presently. The agitator or dasher 3 operates with a reversely rotary movement about a vertical axis and swings through an arc of substantially one hundred and eighty degrees during its operation.

The operation of the agitator 3 is under control of the lever 5 which is provided with a control handle (not shown) for its manipulation. The control lever 5 is capable of occupying three fixed positions. In the first position the motor 4 is inoperative; in the second position the motor is connected to an electric circuit and thus placed in operation; and in the third position the washing machine agitator 3 is connected in operated relation with the washing machine gearing and the driving motor.

The water and clothes contained in the washer tub are given a vortex movement by the to and fro rotation of the agitator 3, and in this manner the clothes are quickly and effectively washed. The agitator 3 is provided with three circumferentially spaced vertical vanes 6 which extend upwardly from a frusto-conical base plate 7. The vanes of the agitator are extended beyond the margin of the base plate 7 for the purpose of preventing the clothes from getting underneath the downwardly turned edge 8 of the base plate.

As a further means for preventing the clothes from getting underneath the edge 8 of the base plate, the tub is provided with a conical raised portion 10, which extends upwardly into the conical base 7 of the agitator. The downwardly turned edge 8, of the agitator base closely approaches the conical upraised portion 10 of the

tub bottom at a point some distance above the point where this part of the tub merges into the surrounding horizontally disposed portion of the tub bottom.

5 As previously stated, the operation of the agitator induces a vortex movement of the contents of the tub. The relative movement of the water and clothes with reference to the central portion of the tub bottom, is outwardly and upwardly and then inwardly and downwardly.

10 The contour of the agitator base and the exposed area of the upraised portion of the tub bottom conforms at this point, approximately 15 to the flow lines of the moving contents of the tub when the machine is in operation. This arrangement permits better circulation of the tub contents with a smaller power consumption than would be possible with the use of an agitator base, the shape of which tended to oppose the 20 flow of the tub contents or which varied greatly from the flow lines of the moving contents of the tub.

15 The natural counter-flow induced at the outermost edges 11, of the trailing face of vanes 6, is not sufficient to throw the clothes against the marginal edge of the agitator base on account of the relatively great distance between these points, and in the normal operation of the machine, the 25 movement of the clothes is always in a direction away from such marginal edge.

20 Under abnormal conditions, such as when the machine is loaded with an excessive amount of clothes, the extended portions 11 of the vanes 35 operate to sweep the clothes clear of the line where the agitator base approaches the tub bottom.

25 The agitator 3, is removably secured to its operating shaft 12, by means of an elongated bolt 40 13. The end 14, of the agitator shaft, is prismatic in shape and has a plurality of flat sides which taper upwardly towards the axis of the shaft. The agitator base is provided with a central socket 15 of complementary form to the prismatic 45 end 14 of the shaft, for receiving this end of the agitator shaft. This arrangement provides a detachable driving connection between the shaft 12 and the agitator 3. The end of the shaft 12 is internally threaded for receiving the bolt 13, by 50 means of which the agitator is securely held in place on its shaft.

30 The washer mechanism gearing of this invention is confined within a two-part gear case, the base 16 of which is used to support the motor 4. 55 The mechanism in the gear case is driven by the motor 4, by means of a V belt 17, which engages the motor pulley 18, and the mechanism pulley 20. A cover 21 is provided for the aforesaid belts and pulleys.

35 60 A centrifugal clutch, which is formed in part by the motor pulley 18, is provided to permit the motor to come up to speed before the load of driving the washing machine mechanism is imposed upon it. This clutch is of similar construction 65 to the clutch illustrated in copending U. S. Patent application Serial Number 497,678 which was filed by W. A. Frantz and A. W. Seyfried, November 24, 1930.

40 In the form of clutch just referred to, a centrifugally operated clutch member 23 is fixedly connected to the motor shaft 24. A clutch drum 25, is integrally formed with the pulley 20. The drum and pulley are rotatably journaled on the motor shaft and when the motor comes up to 45 50 speed, the centrifugally operated part 23 of the

clutch, frictionally engages the drum 25 and drives the pulley at the same speed as that of the motor shaft. If an overload is imposed upon the motor, the clutch immediately begins to slip and thus prevents any damage to the motor.

5

The motor 4 is secured to the gear case base 16, by means of a pair of stamped metal plates 26 and 27. These plates are formed with complementary channels between which there is received a rubber sleeve 28 and a supporting shaft 10 30 which it incloses. The motor 4 is pivotally suspended from the projecting ears 31 of the gear case, which are apertured for receiving the uncovered ends of the shaft 30. The stamped metal motor supporting members 26 and 27 are secured 15 to the motor and to each other by means of a pair of bolts 32.

The lower supporting plate 27 is provided with an extending arm 33, which is engaged between the spring 34 and a wing nut 35. The spring 20 34 is compressed between the arm 33 and the gear case base 16 and it serves to resiliently hold the arm in contact with the wing nut 35. The wing nut is threaded onto a rod 36, the upper end of which is screwed into a boss 37, formed 25 on the base 16 of the gear case. The boss 37 also serves to position and guide the spring 34, which surrounds it. The end of the arm 33 is slotted at 38 for reception of the bolt 36.

A pair of dielectric washers 40 and 41 are provided to insulate the arm 33 from the spring 34 and the nut 35. The upper washer 40 is engaged by the spring 34 and the lower washer 41 is engaged by the wing nut. The provision of the washers just mentioned, and the rubber sleeve 35 28, which forms a sheath for the shaft 30, serves to electrically insulate the motor 4 from the rest of the machine. The sleeve 28 has flanged ends 42, for preventing contact between the plates 26 and 27 and the ears 31.

40

The spring 34 is arranged to resiliently oppose the pull of the belt 17 and it co-operates with the rubber sleeve 28 to provide a resilient and flexible mounting for the motor 4. By this arrangement the motor noises are not transmitted 45 to and amplified by the rest of the machine and an extreme degree of quietness in operation is attained by reason of such construction.

The lower half or base 16 of the gear case, may be constructed in the form of a metal casting. The mechanism belt pulley 20 is fixedly placed at one end in an anti-friction bearing 44. An oil seal 45 is provided between the shaft part 46 and the gear case to prevent the escape of oil at this 55 point. The opposite end of the worm shaft 43 is journaled in a plain bearing 47, formed in the gear case base. An oil seal 48 is also provided in the end of this bearing to prevent the escape of oil at this point from the gear case. A worm 50 60 is threadably secured to the shaft 43.

The lower end of the agitator shaft 12 is journaled in a bearing 51, which is formed in the boss 37 of the gear case base. The shaft 12 provides a bearing for a worm gear 52, which meshes 65 with the worm 50. An eccentric 53 having a hole 54, adjacent to its marginal edge for the receiving of the agitator shaft 12, is fixedly secured to the top of the worm gear 52 by means of the bolt 55, which is screwed into the gear 52.

70

A connecting rod or pitman 56, receives the eccentric 53 in a suitable bearing 57, formed in one of its ends. The rod 56 is held in place on the eccentric by means of a plate 58 which is fitted over the top of the eccentric and which ex- 75

tends beyond the edge of the eccentric to cover the bearing portion 57 of the connecting rod. The plate 58 is held in position by means of a plurality of drive screws 60, which are driven in the 5 drilled holes of the bosses 61 of the eccentric.

The opposite end of the connecting rod 56 is provided with a hole in which a bearing pin 62 is riveted. The pin 62 is journaled in a bearing 63, which is formed in the curved rack bar 64. The 10 pin 62 is held in place in the rack bar 64, by means of a plate 65, which is secured to the pin 62 by the drive screw 66. The rack bar 64 is slidably fitted in a laterally movable bearing member 67. The side 68 of the curved rack bar, which 15 is opposite to the side upon which its gear teeth 70 are cut, is H-shaped in cross section. This part of the bar is smoothly finished and is received in a channel 71 of the bearing member 67, which is C-shaped in cross section. The rectangular 20 base 72 of the bearing member 67 is received in a channel member 73, which is fixedly secured to the gear case base by means of the drive screws 74.

The lateral movement of the bearing member 67 is effected by means of a pinion 75, which 25 meshes with the rack teeth 76, formed in the opening 71, which is provided through the bearing member 67. The pinion 75 is in the form of an elongated mutilated gear having a sufficient number of teeth 78 formed thereon, to shift the bearing member a slight distance back and forth in its guideway 73.

The pinion 75 is provided with an enlarged cylindrical lower end 80, which is journaled in a suitable bearing 81 formed in the base of the 35 gear case. The gear teeth 70 of the rack bar engage with the gear teeth of a pinion 82, which is fixedly secured to the agitator shaft 12, by means of a key 83.

From the foregoing it is apparent that during 40 the time of operation of the motor 4, the worm 50, the worm gear 52 and the eccentric 53 are continuously driven, the latter two elements being rotated about the agitator shaft 12, as a bearing pin. At the same time the connecting rod 56 reciprocates the curved rack bar 64 back and forth 45 in its slideway 71, and this movement of the rack bar is transmitted through the pinion 82 to the agitator shaft 12, giving it a reversely rotary angular movement of substantially one hundred 50 and eighty degrees in each direction. It is understood, of course, that such movement of the agitator shaft takes place only when the rack bar 64 is in mesh with the agitator shaft pinion.

The bearing hole 63 of the rack bar, is placed 55 at a considerable distance from the agitator shaft pinion 82, so that the direction of the force transmitted by the pitman 56 to the rack bar 64 closely approaches a direction tangent to the curvature 60 of the rack bar. This arrangement insures a free running mechanism with low frictional power losses.

The driving of the agitator shaft may be controlled at will by simply rotating in one direction or the other, the pinion 75, which controls the 65 position of the rack bar bearing member 67. The agitator shaft 12 provides a bearing member for the worm gear 52 and its associated eccentric 53, thus permitting a very compact arrangement of the elements of such a mechanism while at the 70 same time eliminating several parts, such as the worm gear supporting shaft and its associated bearings which are customarily employed in such mechanisms.

The upper end of the rack bar shifting pinion 75, is received in a central opening of comple-

mentary form, provided by the segmental pinion 84. The segmental pinion 84, is securely held in place on the pinion 75 by means of the bolt 85, which screws into the pinion 75 and holds a plate 79 against the pinion 84. The segmental pinion 84, is operatively geared to a shifting quadrant 86. This quadrant has gear teeth 87, which mesh with the gear teeth of the pinion 84.

The quadrant 86, is rotatably supported about the agitator shaft bearing member 88, and is held 10 in position thereto by means of the plates or clips 90, integrally formed on the bearing member 88. A plurality of bolts 91 serve to hold the bearing member in place on the gear case cover 92. The shifting quadrant has an integrally formed arm 15 93, to which the shifting lever 5 is secured by means of the bolts 94.

The gear case cover 92 may be formed from a metal stamping with suitable openings for the agitator shaft bearing 88, and the segment shifting pinion 75. An annular bearing 95, is pressed out of the gear case cover for receiving and providing a bearing for the depending sleeve 96 of the segmental pinion 84. This pinion is also provided with a downwardly turned outer edge 97, which is 25 provided for the purpose of retaining the packing ring 98 in place. The packing ring 98 is provided to prevent the escape of oil from the gear case to the bearing 95.

The gear case cover is formed with an out- 30 wardly turned edge 100, for engaging the correspondingly formed top edge 101 of the cast metal base of the gear case. A plurality of bolts 102, are used to secure the upper and lower portions of the gear case to each other. An annular ring 35 103, is welded to the under side of the gear case cover about an opening which is provided to receive the bearing member 88. The ring 103 is provided to strengthen and thicken the gear case cover at this point so that it may be drilled and 40 tapped for receiving the bolts 91, provided to hold the bearing member 88 in place on the gear case cover.

The bearing member 88 is provided with an 45 upstanding sleeve 104 which forms an annular cup for catching and retaining the small amount of oil or grease which may escape from either the packing material 105 provided to seal the shaft 12, or from the gear case itself, by way of the agitator shaft bearing.

Should an unusual amount of oil collect in the cup, the capillary attraction of the packing 50 105 will tend to take up some of it, while gravity also acts to return such oil to the gear case. If desired, the cup may be packed with hard grease 55 to better insure the lubrication of the shaft packing and the shaft bearing over an extended period of time and thus assist in preventing the escape of water from the tub and oil from the gear case.

It is preferred, however, to form the bearing 60 88 with an inner cup 106 and insert at this point a packing ring or washer 107. When this form of construction is used the shaft 12 is slotted as at 108 for the feeding of oil from the gear case 65 to the upper agitator shaft bearing. Excess oil in the cup 106 is returned to the gear case by way of the hole 110.

The packing material 105 is retained in an exteriorly threaded cup-like die cast member 70 111, which is arranged to extend through a central opening provided in the bottom of the tub 1. The member 111 is held in position by means of an upper die-cast lock nut 112 and a lower die-cast internally threaded flanged cup 113, which 75

engages with the threads formed on the member 111 and thus they serve to clamp the tub between the face of the nut and the flange of the cup 113. Suitable gaskets 114 and 115 are used between tub and the nuts 112 and the flange of the cup 113 to effect a liquid-tight seal at this point.

The packing material 105 is automatically maintained in the fluid-tight adjustment about 10 the shaft 12, by means of a slidably fitted packing gland 116 and a flat spiral spring 117, which is interposed between the cup 113 and the gland 116.

The cup 113 and the inner face of the upwardly extending sleeve or collar 104 of the bearing member 88 are formed with a plurality of complementary and coacting flat sides or faces. The cup 113 is loosely fitted in the sleeve 104 of the bearing member 88. The complementary flat 20 sides of the cup 113 and the sleeve 104 cooperate with each other to prevent the nut 112 from unthreading itself from the inner cup 111 and also serve to hold the cup from turning, thus facilitating the application or removal of the 25 unit 112. The packing means just described, is supported entirely by the tub bottom and is free to move on the shaft which it seals to take care of irregularities in the fitting of the parts of the machine and to permit relative movement between the tub and the operating mechanism.

Should it ever be necessary to renew the packing material, the cup 111 can be readily removed through the tub bottom for this purpose, without disturbing the rest of the machine.

35 The gear shifting pinion 84 and quadrant 86 and the agitator shaft bearing 88 may be constructed of die castings to eliminate a large number of machining and other finishing operations on such parts. The bearing member 67, for the 40 rack bar 64 also may be constructed of a die casting.

A spiral groove 125 is formed on a portion of that part of the worm shaft 43, which is received in the bearing 47. One end of the spiral groove 45 125 is in contact with the oil in the gear case and during the rotation of the shaft, the spiral groove causes oil to be forced into the annular groove 126 which is cut in the shaft at the opposite end of the spiral groove. The bearing 45 50 is drilled at a point opposite to the annular groove 126 for the reception of the oil pipe 127. This pipe communicates with the annular groove 126 and conducts oil therefrom to the top surface of the member 67.

55 The web 128 of the member 67 is located on a lower level than the marginal edges of this member and thus provides therewith a shallow open container which is capable of holding considerable amount of lubricant. A channel 130, 60 is cut in the top of the C shaped guideway 11 for its lubrication. The rack bar is notched at 131 for the escape of oil from the guideway to a depression 132 provided in the rack bar. Oil from the depressed part of the rack bar flows 65 over the agitator pinion 82 by way of the notch 133.

In this manner a combined gravity and force-feed lubrication system is provided for the working parts of the machine and a very small amount 70 of oil in the gear case will effectively lubricate all of the mechanism in the gear case.

The worm shaft 43 extends through the gear case at the bearing 47 and is there connected to a horizontal drive shaft 134, by means of a universal joint 135. The universal joint is provided

with a cover 136 for retaining a supply of grease about the joint. The opposite end of the drive shaft 134 is connected to a wringer gearing (not shown).

The lower half 16 of the base of the agitator driving mechanism gear case, is provided with three ears 137, upon which are formed the pads 138. These pads are ground level with the top of the gear case and are drilled at 140 for the reception of the bolts (not shown) by means 10 of which the gear case is secured to the stamped metal base 2.

As a means for facilitating the adjustment of the gear shifting mechanism the segment 86 is provided with a stop 141 which engages with 15 the stop 142 carried by the segmental pinion 84. These stops are intended to be in contact with each other when the curved rack bar 64 is in mesh with the pinion 82. Wear between the curved rack bar and its pinion can be compensated for by removing a small amount of material from the stops 141 and 142.

The modified form of gearing shown in Figures 3 and 7 contemplates the replacement of the curved rack bar 64 and its guiding and supporting member 67 by a segmental gear 143 which is provided with a bearing part 144 at its axis. This bearing part receives a bearing and supporting member 145 which has a base portion 146 arranged for movement in the guideway 13. 30 An axially extending opening 147 is provided in the bearing member and one of the sides of this opening is formed with gear teeth 148 which cooperate with the gear teeth of the mutilated pinion 75. At one of its edges the segmental 35 gear 143 is provided with a bearing 150 for receiving the pin 63 of the connecting rod 56.

The segmental gear is provided with a web portion 151 which forms a shallow pan for the reception of oil discharged from the oil pipe 127. 40 A slot 152 is cut in a toothed portion of the segment so that oil will flow therefrom on to the agitator pinion 82. The remaining parts of the mechanism are identical with those shown in the other views of the drawings and the gearing 45 shown in Figures 3 and 7 is interchangeable with the corresponding parts of the mechanism shown in the remaining Figures of the drawings.

Furthermore it is to be understood that the particular forms of apparatus shown and described, and the particular procedure set forth are presented for the purposes of explanation and that various modifications of said apparatus and procedure can be made without departing from this invention as described in the appended 55 claims.

Having thus described our invention, what we claim is:

1. In a gearing for converting rotating to oscillating motion for laundry machines and the like, a supporting structure, bearings carried by said structure, an oscillatable shaft journaled in said bearings, an eccentric journaled on said shaft, means for revolving said eccentric, a pitman connected at one end to said eccentric and 60 driven thereby, a pinion fixed on said shaft, a gear segment mounted for movement in said structure and connected to the other end of said pitman for oscillating said pinion and shaft, and means for shifting said gear segment into and 65 out of mesh with said pinion to control the operation of said shaft.

2. In a gearing for converting rotating to oscillating motion for laundry machines and the like, a supporting structure, bearings carried by 75

5 said structure, an oscillatable shaft journaled in said bearings, an eccentric journaled on said shaft, means for revolving said eccentric, a pitman connected at one end to said eccentric and driven thereby, a pinion fixed on said shaft, a gear segment mounted for movement on said structure and connected to the other end of said pitman for oscillating said pinion and shaft, a bearing member for said gear segment, and a guideway for said bearing member.

10 3. In a laundry machine, a liquid-tight casing, laundering means in said casing, a base member carrying said casing, and operating means for said laundering means comprising, a supporting structure secured to said base, bearings carried to said structure, an oscillatable shaft journaled in said bearings and operatively connected to said laundering means, an eccentric journaled on said shaft, means for revolving said eccentric, a pitman connected at one end to said eccentric and driven thereby, a pinion fixed on said shaft, a gear segment mounted for movement in said structure and connected to the other end of said pitman for oscillating said pinion and shaft, a bearing member for said gear segment, a guideway for said bearing member, and means for shifting said bearing member in said guideway to connect and disconnect the driving connection between said gear segment and said pinion.

15 4. In a laundry machine, a liquid-tight casing, laundering means in said casing, a base member carrying said casing, and operating means for said laundering means comprising, a supporting structure secured to said base, bearings carried by said structure, an oscillatable shaft journaled in said bearings and operatively connected to said laundering means, an eccentric journaled on said shaft, means for revolving said eccentric, a pitman connected at one end to said eccentric and driven thereby, a pinion fixed on said shaft, a gear segment mounted for movement in said structure and connected to the other end of said pitman for oscillating said pinion and shaft, a bearing member for said gear segment, a guideway for said bearing member, and means for shifting said bearing member in said guideway to connect and disconnect the driving connection between said gear segment and said pinion.

20 5. In a laundry machine, a liquid-tight casing, laundering means in said casing, a base member carrying said casing, and operating means for said laundering means comprising, a supporting structure secured to said base, bearings carried in said structure, a shaft journaled for rotation in said bearings and operatively connected to said laundering means, an eccentric journaled on said shaft, means for revolving said eccentric, a pitman connected at one end to said eccentric and driven thereby, a pinion fixed on said shaft, a gear segment mounted for movement in said structure and connected to the other end of said pitman for oscillating said pinion and shaft, a bearing member for said gear segment, a guideway for said bearing member, and means including movement compounding connections for shifting said bearing member in said guideway to connect and disconnect the driving connection between said gear segment and said pinion.

25 6. In a gearing for converting rotating to oscillating motion for laundry machines and the like, a supporting structure, bearings carried by said structure, a shaft journaled for rotation in

30 said bearings, an eccentric journaled on said shaft, means for revolving said eccentric, a pitman connected at one end to said eccentric and driven thereby, a pinion fixed on said shaft, a gear segment connected to the other end of said pitman for oscillating said pinion and shaft, a bearing member for said gear segment, a guideway for said bearing member, and means including a pinion and rack teeth formed on said bearing member and movement compounding means connected to such pinion for shifting said bearing member in said guideway to connect and disconnect the driving connection between said first named gear segment and said pinion.

35 7. In a laundry machine, a liquid-tight casing, laundering means in said casing, a base member carrying said casing, and operating means for said laundering means comprising a supporting structure secured to said base, an agitator shaft journaled for oscillation in said structure and operatively connected to said laundering means, a pinion fixed on said shaft, a non-rotatable bearing pin mounted for bodily movement in said supporting structure, a gear segment journaled on said pin, means for oscillating said gear segment, and means for laterally shifting said pin to throw said gear segment and pinion into and out of mesh.

40 8. In a laundry machine, a liquid-tight casing, laundering means in said casing, a base member carrying said casing, and operating means for said laundering means comprising a supporting structure secured to said base, an agitator shaft journaled for rotation in said structure and operatively connected to said laundering means, a pinion fixed on said shaft, a hollow non-rotatable stub shaft mounted for bodily movement in said supporting structure, a gear segment journaled on said stub shaft, means for oscillating said gear segment, and means within said stub shaft for effecting the lateral movement thereof to throw said gear segment and pinion into and out of mesh.

45 9. In a clutching device for the operating mechanism of washing machines, a supporting structure, an agitator shaft journaled for rotation in said structure, a pinion fixed on said shaft, a hollow non-rotatable stub shaft mounted for bodily movement in said supporting structure, a gear segment journaled on said shaft, means for oscillating said gear segment, vertical rack teeth formed on one side of the hollow interior of said stub shaft, and a second pinion engaging said rack teeth for laterally shifting said stub shaft to throw said gear segment and first named pinion into and out of mesh.

50 10. In a laundry machine, a liquid-tight casing, laundering means in said casing, a base member carrying said casing, and operating means for said laundering means comprising a supporting structure secured to said base, an agitator shaft journaled for rotation in said structure and operatively connected to said laundering means, a pinion fixed on said shaft, a non-rotatable stub shaft mounted in said supporting structure, means for supporting said stub shaft for bodily lateral movement, a gear segment journaled on said stub shaft, means for oscillating said gear segment, and means for laterally shifting said stub shaft to throw said gear segment and pinion into and out of mesh.

55 11. In a laundry machine, a liquid-tight casing, laundering means in said casing, a base member carrying said casing, and operating means for said laundering means comprising a supporting

- structure secured to said base, an agitator shaft journaled for rotation in said structure and operatively connected to said laundering means, a pinion fixed on said shaft, a stub shaft mounted for non-rotatable movement in said supporting structure, a gear segment journaled on said stub shaft, means for oscillating said gear segment, vertical rack teeth formed on one side of an axial opening extending through said stub shaft, a second pinion engaging said rack teeth for laterally shifting said stub shaft to throw said gear segment and first named pinion into and out of mesh, and means to rotate said second pinion.
12. In a clutching device for the operating mechanism of washing machines, a supporting structure, an agitator shaft journaled for rotation in said structure, a pinion fixed on said shaft, a hollow stub shaft mounted for non-rotatable movement in said supporting structure, a gear segment journaled on said stub shaft, means for oscillating said gear segment, vertical rack teeth formed in the interior of said stub shaft, a second pinion engaging said rack teeth for laterally shifting said stub shaft to throw said gear segment and first named pinion into and out of mesh, and lever means to rotate said second pinion.
13. In a laundry machine, a liquid-tight casing, laundering means in said casing, a base member carrying said casing, and operating means for said laundering means comprising a supporting structure secured to said base, an agitator shaft journaled for rotation in said structure and operatively connected to said laundering means, a pinion fixed on said shaft, a stub shaft mounted for non-rotatable movement in said supporting structure, a gear segment journaled on said stub shaft, means for oscillating said gear segment, vertical rack teeth formed on one side of an axial opening extending through said stub shaft, a second pinion engaging said rack teeth for laterally shifting said stub shaft to throw said gear segment and first named pinion into and out of mesh, lever means to rotate said second pinion, and stops for fixing the adjusted positions of said lever means.
14. In a laundry machine, a liquid-tight casing, laundering means in said casing, a base member carrying said casing, and operating means for said laundering means comprising a supporting structure secured to said base, an agitator shaft journaled for rotation in said structure and operatively connected to said laundering means, a pinion fixed on said shaft, a stub shaft mounted for non-rotatable movement in said supporting structure, a gear segment journaled on said stub shaft, means for oscillating said gear segment, vertical rack teeth formed on one side of an axial opening extending through said stub shaft, a second pinion engaging said rack teeth for laterally shifting said stub shaft to throw said gear segment and first named pinion into and out of mesh, lever means to rotate said second pinion, and movement compounding means connecting said lever means to said second pinion.
15. In a clutching device for the operating mechanism of washing machines, a supporting structure, an agitator shaft journaled for rotation in said structure, a pinion fixed on said shaft, a hollow stub shaft mounted for non-rotatable movement in said supporting structure, a gear segment journaled on said shaft, means for os-

cillating said gear segment, vertical rack teeth formed in the interior of said stub shaft, a second pinion engaging said rack teeth for laterally shifting said stub shaft to throw said gear segment and first named pinion into and out of mesh, and means for rotating said second pinion including a lever accessible from the exterior of the machine and movement compounding gearing connecting said lever to said second pinion.

16. In a gearing for converting rotating to oscillating motion for laundry machines and the like, a supporting structure, bearings carried by said structure, an oscillatable shaft journaled in said bearings, an eccentric journaled on said shaft, means for revolving said eccentric, a pitman connected at one end to said eccentric and driven thereby, a pinion fixed on said shaft, a gear segment mounted for movement in said structure and connected to the other end of said pitman for oscillating said pinion and shaft, and means including an element rotatable about the axis of said shaft for shifting said gear segment into and out of mesh with said pinion to control the operation of said shaft.

17. In a gearing for converting rotating to oscillating motion for laundry machines and the like, a supporting structure, bearings carried by said structure, an oscillatable shaft journaled in said bearings, an eccentric journaled on said shaft, means for revolving said eccentric, a pitman connected at one end to said eccentric and driven thereby, a pinion fixed on said shaft, and a gear segment mounted for movement in said structure and connected to the other end of said pitman for oscillating said pinion and shaft.

18. In a gearing for converting rotating to oscillating motion for laundry machines and the like, a supporting structure, bearings carried by said structure, an oscillatable shaft journaled in said bearings, an eccentric journaled on said shaft, a reduction gear journaled on said shaft for revolving said eccentric, a pitman connected at one end to said eccentric and driven thereby, a pinion fixed on said shaft, and a gear segment mounted for movement in said structure and connected to the other end of said pitman for oscillating said pinion and shaft.

19. A motion converting gearing comprising a gear case, aligned bearings in opposite walls of said gear case, a shaft journaled in said bearings, a pinion fixed to said shaft, a toothed member for oscillating said pinion and shaft, means journaled for rotation on said shaft, and an off center connection between said means and said toothed member for driving the same with a back and forth motion.

20. A motion converting gearing comprising a lubricant retaining gear case, spaced aligned bearings mounted in opposite walls of said gear case, a shaft journaled in said bearings, a pinion, an eccentric and a reduction gear arranged in said gear case on said shaft in the order named, said pinion being fixed to said shaft, said reduction gear and eccentric being secured to each other and freely rotatable upon said shaft, means for driving said reduction gear, a toothed member meshing with said pinion, and a pitman connecting said eccentric to said toothed member.
